UNITED STATES PATENT OFFICE.

ORA D. MCCLURE, OF ISHPEMING, MICHIGAN.

STEEL FRAMING FOR MINE-SHAFTS.

1,294,814.

Specification of Letters Patent. Patented Feb. 18, 1919.

Application filed October 30, 1916. Serial No. 128,418.

To all whom it may concern:

Be it known that I, ORA D. MCCLURE, a citizen of the United States, and a resident of Ishpeming, county of Marquette, and 5 State of Michigan, have invented certain new and useful Improvements in Steel Framings for Mine-Shafts, of which the following is a full, clear, and exact description.

10 The present invention relates to steel framing for supporting the lining, cage guides and the like of mine shafts. In accordance with the present practice, the framing of mine shafts, whether of wood or 15 steel, comprises a series of horizontal frames or so called "sets" with vertical frame members interposed between the sets. Each horizontal frame or set comprises outer side members arranged closely adjacent the 20 wall of the mine shaft and cross members for supporting the cage guides and the like. Usually the side members of the sets are connected to one another at the corners thereof, and also, at such points, to the ends 25 of vertical members which are interposed between the sets. In the confined quarters of a mine shaft it is difficult to support the heavy frame members of the sets and properly join them to one another and to the 30 ends of the vertical spacing members.

The present invention seeks to overcome this difficulty and provide a construction in which the frame members of the sets can be readily supported and secured in position 35 within the mine shaft and in which strong securing joints can be readily formed between the members of the frame work. The invention consists in the features of improvement hereinafter set forth illustrated 40 in the preferred form in the accompanying drawings and more particularly pointed out in the appended claims.

In the drawings, Figure 1 is a horizontal section of the improved construction taken 45 on the line 1—1 of Fig. 2. Fig. 2 is a vertical section on the line 2—2 of Fig. 1. Fig. 3 is an inverted plan detail, parts being shown in section on the line 3—3 of Fig. 2. Fig. 4 is a detail section on the line 4—4 of 50 Fig. 3.

As shown, each horizontal frame or set comprises side members 10 which are preferably formed of I-beams having their webs horizontally disposed and their edge 55 flanges vertical. The side members 10 of the horizontal frame or set preferably ex-

tend continuously between the corners thereof. The ends of the frame members at the corners are mitered or beveled at an angle of 45° and are connected by angle 60 brackets 11. Each of these angle brackets is securely riveted to one of the side members and is bolted to the adjacent side member when the frame is assembled within the mine shaft. To strengthen the horizontal 65 web portions of the I-beams 10 angle bars 12 having vertically disposed flanges are centrally riveted to the upper and lower faces thereof.

Each horizontal frame or set carries cross 70 beams and cage guides which can be variously arranged to suit different conditions. In the construction shown a cross beam 13 extends between two opposite side members 10 and a cross beam 14 extends between the 75 beam 13 and one of the side members. Angle brackets 15 are riveted to the ends of the cross beams and, when the frame is assembled within the mine shaft, are bolted to the vertical flanges of the I-beams 10 and 80 to the web of the cross beam 13.

The vertical members for connecting or spacing the frames or sets are not connected at their ends thereto but extend continuously past the same. Preferably these vertical 85 members are in the form of heavy angle bars 16 which are arranged outside of and extend past the corners of the horizontal frames or sets and are provided with angle brackets 17 for supporting the 90 frame members 10 at their ends or at the corner of each set. Each of the angle brackets is securely riveted to the vertical spacing or connecting angle bar 16 and extends beneath the beveled ends of the side 95 members 10. To provide a firm support for the side members 10 on the bracket 17, spacing plates 18 are preferably secured to the adjacent beveled ends of the side members. These spacing plates are securely riveted to 100 the end of one of the side members and are bolted to the end of the adjacent side member when the latter are assembled in the mine shaft. Connecting bolts 19 extend centrally through the spacing plates 105 and the supporting brackets 17.

The abutting ends of the vertical angle members 16 are securely connected at points intermediate the separate sets by fish plates 20 which are riveted to one of the members 110 16 and when the parts are assembled in the mine shaft are bolted to the adjacent mem-

ber. Vertical channel bars 21 for supporting wooden cage guides 22 also extend between the separate sets. These channel bars are connected to the cross bars 13 and 14 by brackets 23, and to the vertical flanges of the side members 10 by bolts 24 having spacing sleeves 25 thereon.

In assembling the framing in the mine shaft as the latter is excavated, the vertical corner spacing members 16 with the brackets 17 riveted thereto are first placed in position. The heavy side members 10 are then put in place with their ends resting upon the brackets 17. The latter thus serve to support the heavy side members 10 while they are being bolted to one another and to the brackets. When the mine shaft is further excavated, another series of vertical members 16 will be secured to the lower ends of the vertical members already in position and another horizontal frame or set mounted thereon. In this way the mine frame work can be readily and economically assembled in the confined quarters of the mine shaft and strong joints formed between the members thereof.

If necessary to sustain the walls of the shaft, a wooden lagging or lining can be interposed between the horizontal frames or sets. The vertical flanges of the beams 10 and of the angle bars 12 will serve to hold the boards of this wooden lagging or lining in place. If desired, the shaft may be provided with a concrete lining, which will be strengthened and held in place by the vertical and horizontal members of the frame work.

It is obvious that changes may be made in the details set forth without departure from the essentials of the invention as defined in the claims.

I claim as my invention:—

1. The method of constructing the framing of mine shafts which consists first in placing within the shaft a set of vertical spacing members having supporting brackets

fixed thereto intermediate their end portions, then lowering upon said brackets horizontal side frames and securing the abutting ends of said side frames to aid said brackets, and thereafter successively securing to the lower ends of said vertical members additional vertical members having brackets fixed thereto intermediate their end portions and lowering upon and securing to said brackets horizontal side frames.

2. A steel framing for mine shafts, comprising a series of vertically arranged spacing members formed of angle bars and having brackets secured thereto in the angles of said bars intermediate their ends, at which points said vertical members are connected, and a series of superposed horizontal frames formed of continuous bars having their ends connected to each other and disposed within the angles of said spacing bars and secured to and resting on top of said brackets.

3. In a steel framing for mine shafts, the combination of a number of horizontal frames, comprising side members connected at their ends, vertical spacing members formed of angle bars extending continuously past and outside of the corners of said frames, and connected together at points intermediate said frames, and inwardly projecting supporting brackets secured to said vertical angle bars and extending beneath the ends of said side members, substantially as described.

4. In a steel framing for mine shafts, the combination of a number of horizontal frames comprising structural side members having horizontal webs, vertical flanges and mitered ends, vertical angle bars extending past and outside the corners of said frames, brackets secured to said angle bars and projecting inwardly beneath the ends of said side members, and space plates interposed between and secured to said side members and said brackets, substantially as described.

ORA D. McClure.
